UNITED STATES PATENT OFFICE.

LINDSEY E. HOLCOM, OF TWISP, WASHINGTON.

SNAP-HOOK.

1,221,744.

Specification of Letters Patent.

Patented May 1, 1917.

Application filed May 1, 1914. Serial No. 835,659.

To all whom it may concern:

Be it known that I, LINDSEY E. HOLCOM, a citizen of the United States, residing at Twisp, in the county of Okanogan and State of Washington, have invented new and useful Improvements in Snap-Hooks, of which the following is a specification.

This invention relates to snap hooks, and more especially to those having sliding spring-pressed mousings; and the object of the same is to produce an article of this character having twin hooks standing alongside each other and opening in opposite directions so that a ring or link may be inserted 10 between the hooks and then turned to pass it through their throats simultaneously, and independent mousings normally closing both the throats and capable of being manually retracted by force applied purposely to both 15 the handles simultaneously, before the ring or link can be released.

With the above and other objects in view, the improvement resides in the construction, combination and arrangement of parts set 20 forth in the following specification and falling within the scope of the appended claims.

In the drawing:—

Figure 1 is a perspective view of a snap hook constructed in accordance with the 25 present invention,

Fig. 2 is a bottom plan view of the same, Fig. 3 is a central longitudinal sectional view through the same,

Fig. 4 is an end view, and

Fig. 5 is a transverse section approximately on the line 5—5 of Fig. 2.

Referring now to the drawing in detail, 1 designates the shank or body of the hook, which preferably comprises an elongated 5 substantially rectangular member which may have its corners rounded. The shank 1 at one of its ends is formed with a transverse recess or opening 2, the rear wall of which being provided with a central reduced opening 3 for the reception of the shank 4 of an eye 5. The end of the shank 4 within the opening 2 is formed with a head 6, whereby the eye is swiveled to the shank 1. The other end of the body is provided with a 10 deep longitudinal slot 7 by which it is forked or bifurcated, the arms of the bifurcation standing on edge and being spaced slightly from each other. Said arms carry two hooks 8 and 9 which may be called twin hooks as 15 they are duplicates of each other, stand side by side and parallel, are spaced by the width

of the slot 7, and differ only in that the throat of the hook 8 as shown in Fig. 1 is uppermost and opposite the shank of the hook 9, whereas the throat of the latter is 60 at the bottom as appears in Fig. 2. The end of each arm is by preference provided with an abrupt and substantially flat face 17, the two faces being alined transversely of the structure, and as seen in Fig. 1 the shank 65 of the hook 8 is integral with the nearer arm and deflected downward therefrom just in rear of such face, its bend is parallel with that of the hook 9, and its bill is bent back so that it is directed straight toward said 70 face 17 near the upper edge of the nearer arm, being spaced therefrom by the width of the throat of this hook. Across this throat stands the mousing which I preferably make in the shape of a bolt 10 slidably mounted in 75 a chamber which is bored into the arm in direct alinement with the bill of the hook, and normally projected by an expansive spring 14 in the rear end of said chamber as seen in Fig. 2. A longitudinal slot 12 opens from 80 said chamber through the upper edge of this arm throughout the proper length, and a handle 11 projecting radially from the bolt passes through this slot and has a suitable head on its upper end as indicated. The 85 bolt 13 and its handle 15 are mounted in the other or remote arm of Fig. 1 in the same manner, as will be best seen in Fig. 2, but it is important to note that the heads of the handles 11 and 15 are exposed on opposite 90 faces of the body 1 of the structure, the former on the upper edge of one arm and the latter on the lower edge of the other. The numeral 16 is applied to a ring as shown in Fig. 1 as of sufficient size to pass through 95 both hooks 8 and 9, but it often occurs that an oblong link of a chain is to be engaged with a snap hook of this character and unless it is turned crosswise it can hardly be made to embrace both hooks. In that case 100 it can be engaged with only one hook, and perhaps another link at the extremity of another stretch of chain can be engaged with the other hook. But whatever the element engaged with this hook, it is held by the 105 mousing, and the particular advantage of the structure described prevails when the element is as large as that indicated by the numeral 16. In arranging the ring 16 upon the hook, the same is first passed within the 110 bifurcated portion 7, one of the bolts, say 10, is forced rearwardly within its chamber

to permit of the ring being inserted within the hook 8. When this is accomplished the bolt 13 is moved away from the hook 9, the ring turned until the same is brought within 5 the said hook. By such an arrangement it will be noted that the ring 16 will be effectively retained by the hook irrespective of the jerking movement imparted to the ring by tossing of the head of the animal to 10 which the strap connecting the ring 16 of the halter is attached, and furthermore that should one of the heads of the spring pressed bolts be contacted and moved to release one of the hooks, the second hook will still retain 15 the ring upon the device.

From the above description, taken in connection with the accompanying drawing, the simplicity of the device, as well as the advantages thereof will, it is thought, be perfectly apparent to those skilled in the art to 20 which such invention appertains without further detailed description.

Having thus described the invention, what I claim is:

25 1. A snap hook comprising a body bifurcated at one end, and spaced parallel hooks carried by the arms of the bifurcation and each having its throat opening laterally and

opposite to the shank of the other; combined with independent means out of line with the 30 space between said hooks for normally closing their throats, and separate handles on such means exposed on relatively opposite edges of said arms.

2. A snap hook comprising a bifurcated 35 body, the arms of the bifurcation having transversely alined abrupt faces and being provided with longitudinal chambers opening through said faces and with slots opening from the chambers through relatively 40 opposite edges of the two arms, bolts in said chambers, springs therein independently projecting the bolts, handles on the latter extending through the respective slots; and twin hooks whose shanks are integral with 45 the respective arms and deflected from their unslotted edges, whose bends are parallel, and whose bills have their tips directed toward and spaced from said faces and each alined with its respective bolt. 50

In testimony whereof I affix my signature in presence of two witnesses.
